JOHN BOCIEK

INVENTOR

BY *Victor J. Evans*

ATTORNEY

UNITED STATES PATENT OFFICE.

JOHN BOCIEK, OF CHICAGO, ILLINOIS.

SWIMMING GLOVE.

Application filed May 12, 1924. Serial No. 712,369.

To all whom it may concern:

Be it known that I, JOHN BOCIEK, a citizen of the United States, residing at Chicago, in the county of Cook and State of Illinois, have invented new and useful Improvements in Swimming Gloves, of which the following is a specification.

This invention relates to a swimming glove and has for its primary object the construction of a glove having the required flexibility so as to be readily manipulated by the hand.

An object of the invention is the novel manner of arranging and attaching finger loops so that the finger loops will be effectively connected to the body while giving the required amount of flexibility to the various fingers and more particularly to the thumb.

20 A feature of my invention is the use of an individual thumb loop strip so as to allow the thumb and its associated portion of the body to be properly shaped to bring about the most efficient engagement between the body and the volume of water.

With these and other objects in view the invention will be better understood from the following detailed description taken in connection with the accompanying drawing 30 wherein:

Fig. 1 is a plan view of the glove.

Fig. 2 is a sectional view on the line 2—2 of Fig. 1.

Again referring to the drawing illustrating one of the many constructions of my invention the numeral 1 designates a hand shaped flexible body to the small end 2 of which is attached the adjustable wrist strap 3. The inner strip 4 and outer strip 5 have spaced portions sewed to the body as indicated at 6 to form an inner and outer series of finger loops 7. To complete the invention I attach to the body an individual

outer thumb looped strip 8. The strips 4 and 5 are preferably curved transversely 45 of the body in order that the finger loops 7 will be properly positioned to receive the respective fingers which are to be positioned within the loops provided for.

From the foregoing description taken in connection with the accompanying drawing it will be seen that the cost of manufacture of the article is greatly reduced without sacrificing the advantages. It will also be noted that the fingers of the operator are 55 engaged at spaced points so as to insure the effective grip between the body and hand and this action is increased by the novel arrangement of the wrist strap.

It is, of course, to be understood that the exact shape and manner of associating the parts may be changed at will without departing from the spirit of this invention, therefore I do not desire to be limited in any manner except as set forth in the claim hereunto appended.

Having thus described my invention what I claim is:

A swimming glove comprising a fan-shaped flexible body, an adjustable wrist 70 strap connected to the smaller end of the body, spaced curved strips attached to the body by transverse rows of stitching arranged in spaced relation to form finger loops longitudinally of the strips, one of 75 said strips being extended entirely across the body to form an individual loop for each of the fingers and thumb of the hand, the other strip being extended partially across the body to form loops for the fingers of the 80 hand and an individual outer thumb sewed to the body and disposed in alignment with the thumb on the first mentioned strip.

In testimony whereof I affix my signature.

JOHN BOCIEK.
